CHARLES R. HARKINS

By *Watson E. Coleman*

Attorney

UNITED STATES PATENT OFFICE.

CHARLES R. HARKINS, OF OTIA, MICHIGAN.

HOSE-PROTECTOR.

1,249,387.

Specification of Letters Patent. Patented Dec. 11, 1917.

Application filed April 18, 1917. Serial No. 163,050.

To all whom it may concern:

Be it known that I, CHARLES R. HARKINS, a citizen of the United States, residing at Otia, in the county of Newaygo and State 5 of Michigan, have invented certain new and useful Improvements in Hose-Protectors, of which the following is a specification, reference being had to the accompanying drawings.

10 This invention relates to certain improvements in hose protectors and it is an object of the invention to provide a device of this general character having novel and improved means whereby a convenient and effective bridge is afforded for protecting hose or the like disposed across a trackway and which protector readily permits the passage of rolling stock over such hose.

20 The invention consists in the details of construction and in the combination and arrangement of the several parts of my improved protector whereby certain important advantages are attained and the device is rendered simpler, less expensive and otherwise 25 more convenient and advantageous for use, all as will be hereinafter more fully set forth.

The novel features of the invention will hereinafter be definitely claimed.

30 In order that my invention may be the better understood, I will now proceed to describe the same with reference to the accompanying drawings, wherein

35 Figure 1 is a view in elevation illustrating a hose protector constructed in accordance with an embodiment of my invention and in applied position;

Fig. 2 is a view in bottom plan of my improved device as herein embodied;

40 Fig. 3 is a sectional view taken substantially on the line 3—3 of Fig. 1; with the supporting tie omitted; and

Fig. 4 is a sectional view taken substantially on the line 4—4 of Fig. 1.

45 As disclosed in the accompanying drawings, R denotes a rail of a standard type supported upon the cross ties T. B denotes my improved bridge or protector and as herein embodied said bridge or protector is substantially U-shape in cross section and adapted to snugly embrace the rail. The depending or side members 1 thereof are provided adjacent their lower ends with the longitudinally disposed shoulders 2 adapted 50 to substantially contact with the upper faces of the base flanges 3 of the rail R.

The bridge or protector B is of a length to rest upon adjacent ties and the lower marginal portions thereof are provided with the outstanding flanges 4 which are adapted 60 to be engaged by spikes or other suitable headed members for maintaining the bridge or protector B substantially fixed when in applied position.

The outer face of the intermediate portion 65 5 of the bridge or protector B is disposed on a predetermined curvature whereby the intermediate or central portion thereof is elevated and the opposite longitudinal margins of said upper face are provided with 70 the grooves or channels 6 to compensate for the flanges of the wheels of the rolling stock.

The inner face of the intermediate portion 75 5 at a predetermined point intermediate its length has its under surface provided with the transverse groove or channel 7 and in communication with the opposite ends of said groove or channel 7 are the open slots 8 produced in the side members 1. The 80 groove or channel 7 is of such a depth as to readily accommodate the portion of a hose H overlying the rail R. It will also be self-evident that the open slots 8 permit the ready application of the bridge or protector 85 B in applied position.

While in the accompanying drawings I have disclosed only a single transverse groove or channel 7 with its coacting open slots 8, it will be understood that the bridge 90 or protector B may be provided with as many of these grooves or channels as the requirements of practice may dictate.

From the foregoing description, it is thought to be obvious that a protector constructed in accordance with my invention is of an extremely simple and comparatively inexpensive nature and is particularly well adapted for use by reason of the convenience and facility with which it may be assembled, 100 and it will also be obvious that my invention is susceptible of some change and modification without material departure from the principles and spirit thereof and for this reason I do not wish to be understood as 105 limiting myself to the precise arrangement and formation of the several parts herein shown in carrying out my invention in practice, except as hereinafter claimed.

I claim:

110 A hose protector comprising a member substantially U-shape in cross section and

adapted to straddle a rail with the intermediate portion thereof uppermost relative to the rail when in applied position, said intermediate portion being disposed on a predetermined longitudinal curvature and provided in its under face with a transversely directed channel, the sides of said protector being provided with open slots in communication with said channel, the free longitudinal margins of the side members of the protector being provided with outstanding flanges, the inner faces of the side members

of the protector being provided adjacent their free longitudinal margins with shoulders adapted to contact with the flanges of 15 the rail to which the protector may be applied.

In testimony whereof I hereunto affix my signature in the presence of two witnesses.

CHARLES R. HARKINS.

Witnesses:

MARY C. HARKINS,
W. C. CANTRELL.
